UNITED STATES PATENT OFFICE.

CHARLES W. COLLYER, OF RANDOLPH, MASSACHUSETTS, ASSIGNOR OF ONE-HALF TO FREDERICK E. CALLER, OF HYDEPARK, MASSACHUSETTS, AND ONE-HALF TO HERBERT M. BRIGGS, OF RANDOLPH, MASSACHUSETTS.

HOLDBACK.

SPECIFICATION forming part of Letters Patent No. 793,420, dated June 27, 1905.

Application filed October 31, 1904. Serial No. 230,622.

To all whom it may concern:

Be it known that I, CHARLES W. COLLYER, a citizen of the United States, residing at Randolph, in the county of Norfolk and State of Massachusetts, have invented certain new and useful Improvements in Holdbacks; and I do hereby declare the following to be a full, clear, and exact description of the invention, such as will enable others skilled in the art to which it appertains to make and use the same.

The present invention relates to holdbacks for vehicles, and more particularly to certain improvements on the holdback disclosed in my Letters Patent of the United States, No. 570,327, of December 5, 1893; and its object is to provide a device of this character in which the retaining-bail may be securely fastened to prevent the release of the shaft-lug or breeching-strap, and thus avoid accidents.

To the above ends the present invention consists of the improved holdback which will now be described and claimed.

My invention is illustrated in the accompanying drawings, in which—

Figure 1 shows the device in side elevation attached to the under side of a thill with the harness-lug shown in dotted lines. Fig. 2 shows a fragmentary detail view of the latch end of the bail, illustrating in cross-section the engagement of the locking-bolt therewith, the parts being inverted. Fig. 3 shows a fragmentary detail view of the end of the locking-bolt, the latch at the end of the swinging bail being shown in cross-section. Fig. 4 is a view similar to that shown in Fig. 3, illustrating the action of the latch on the side of the bolt.

Similar letters of reference will be used throughout the specification and drawings to designate corresponding parts.

In the drawings, A represents a portion of a shaft or thill, and B my improved holdback attached to the under side of the thill A by means of screws C. The holdback comprises a base plate or frame b, formed, preferably, in a single casting and having its under side concave or grooved in a manner well known to

those familiar with this art to fit the curved under surface of the thill or shaft A. The extended end portions b' of the base plate or frame b are provided with openings b², through which pass the screws C, by means of which the device is secured to the shaft or thill A. The base-plate b has a projecting portion c, within which is formed a longitudinal chamber or recess c', (represented by dotted lines in Fig. 1,) and is provided near one end with a bearing c² and near the opposite end with a bearing c³ open at one side, forming an open socket, as indicated at c⁴. The holdback-bail d is substantially U-shaped, and one end thereof, d', is threaded and projects beyond a shoulder d². The threaded end d' passes through an aperture in the bearing c² and within the chamber c is provided with a nut d⁴ and a lock-nut d⁵, by means of which the bail d is held to pivotally turn about an axis coincident with its threaded end d'—that is to say, its forward end may be moved outwardly from under the base-plate b, so as to open the holdback for the admission of the harness-lug, and thence moved inwardly beneath the base-frame b after the lug has been inserted therein. The other end of the bail d is provided with a shoulder and above this with a cylindrical latch end d⁶, which at one side is notched or cut away, as shown at d⁷. To securely retain the latch end of the bail in connection with the base-plate b, there is provided a sliding bolt e, fitted to slide in a bearing e' at the end of the projection c, a bearing e' at the right of the open socket c⁴, and a bearing e' at the left of the open socket c⁴, the bolt e being surrounded by a spiral spring e', one end of which bears against the inner face of the projection c and the other end against a pin e⁵, fitted in said bolt. The outer face of the end of the bolt e is beveled, as shown at e⁶, so that the rounded inner face d⁸ when pushed against the beveled face e⁶ may cause the bolt e to be forced back against the tension of the spring e', thus permitting the latch of the bail d to spring past the end of the bolt in making a locking connection. For the purpose of re-

tracting the bolt *e* against the tension of the spring *e'* it may be provided with any suitable head or thumb piece *e*'.

The operation of my improved holdback 5 is as follows: The bail being opened, the harness-lug is placed therein and the bail then closed and securely locked, thus retaining the lug and affording means whereby the vehicle may be drawn forward or held back by a direct connection with the saddle of the harness. Thus the traces may be dispensed with, if desired, or if used should they become detached or broken there would still be a draft connection between the harness and the vehicle. 15 It is of course understood that the breeching also may be dispensed with; but if used they may be connected also with the holdback.

Having described my invention, I claim as new and desire to protect by Letters Patent of 20 the United States—

1. A holdback comprising a base-plate, a bail having one of its arms pivotally mounted

in said base-plate, a latch formed upon the end of the other arm of said bail, an open socket in said base-plate arranged to receive 25 said latch and a sliding spring-pressed bolt for engaging said latch and retaining it in said socket, substantially as described.

2. A holdback comprising a base-plate, a bail having one of its arms pivotally mounted 30 in said base-plate, a substantially cylindrical notched latch formed upon the end of the other arm of said bail, an open socket in said base-plate arranged to receive said latch and a sliding spring-pressed bolt provided with a 35 beveled end arranged to extend across the open face of the socket and provided with a thumb-piece, substantially as described.

In testimony whereof I affix my signature in presence of two witnesses.

CHARLES W. COLLYER.
